(57) **CLAIM**

The ornamental design for audio eyewear, as shown and described.

DESCRIPTION

FIG. 1 is a front right side perspective view of a first embodiment of audio eyewear in the present invention having clear lenses.

FIG. 2 is a front view thereof.

FIG. 3 is a rear view thereof.

FIG. 4 is a top view thereof.

FIG. 5 is a bottom view thereof.

FIG. 6 is a left side view thereof.

FIG. 7 is a right side view thereof.

FIG. 8 is a rear right side perspective view thereof with speaker members in a down position.

FIG. 9 is a left side view thereof with speaker members in a down position.

FIG. 10 is a right side view thereof with speaker members in a down position.

FIG. 11 is a front right side perspective view of a second embodiment of audio eyewear in the present invention having sunglass lenses.

FIG. 12 is a front view thereof.

FIG. 13 is a rear view thereof.

FIG. 14 is a top view thereof.

FIG. 15 is a bottom view thereof.

FIG. 16 is a left side view thereof.

FIG. 17 is a right side view thereof.

FIG. 18 is a rear right side perspective view thereof with speaking members in a down position.

FIG. 19 is a left side view thereof with speaker members in a down position; and,

FIG. 20 is a right side view thereof with speaker members in a down position.
